UNITED STATES PATENT OFFICE.

CLEMMA R. RANEY, OF CHICAGO, ILLINOIS, ASSIGNOR TO INTERNATIONAL HARVESTER COMPANY OF NEW JERSEY, A CORPORATION OF NEW JERSEY.

GRAIN-SHOCKING MACHINE.

1,215,191.

Specification of Letters Patent.

Patented Feb. 6, 1917.

Application filed October 2, 1913. Serial No. 793,052.

To all whom it may concern:

Be it known that I, CLEMMA R. RANEY, a citizen of the United States, residing at Chicago, in the county of Cook and State of Illinois, have invented certain new and useful Improvements in Grain-Shocking Machines, of which the following is a full, clear, and exact specification.

My invention relates to grain shocking machines.

It has heretofore been proposed to equip such machines with sheaf delivering mechanism in the form of an oscillating sheaf delivery member or fork which, in its sheaf

receiving position, lies beneath the binder deck and is then moved, as each sheaf is ejected from the binder, to its sheaf delivering position over the shocker cradle; the fork thus moving back and forth during the

process of delivering each individual sheaf which goes to make up the shock. Under certain conditions it has also been found advisable, in a construction of this character, to provide means for deflecting the fork

whereby the same is thrown alternately to one side or the other of the cradle in such a manner as to build a shock wherein the sheaves have diverging butts and converging tops.

My invention has for its object to deliver sheaves to the shocker cradle in an improved manner whereby a compact, evenly constructed shock is built without making it necessary to deflect the sheaf delivery member, and the wear upon the mechanism, as well as the cost of manufacture, is materially reduced. I attain these objects by providing improved sheaf positioning and delivering means coöperating with the de-

livery mechanism of the binder and the sheaf forming mechanism of the shocker, whereby a plurality of sheaves are simultaneously supplied to the sheaf delivery member and carried backward into the shocker cradle by this member in such relation that when released by the sheaf delivery member as the latter returns to sheaf receiving position, the sheaves occupy a position in the cradle conducive to the building of a compact shock capable of standing in the field under all conditions.

In the accompanying drawings I have illustrated one embodiment which my invention may assume in practice. It is to be

understood, however, that the form thereof shown herein may be modified.

Figure 1 is a side elevation of a shocker and binder equipped with my improvement;

Fig. 2 is an end elevation of the same, the parts being shown diagrammatically to illustrate more clearly their coöperation with the harvester mechanism;

Fig. 3 is a rear view of the shocker, showing the sheaves in the cradle and the sheaf delivery member as it is withdrawn therefrom.

In the construction shown I have illustrated a shocker of standard construction, comprising a wheeled frame 1, having a sheaf delivery member, or fork, 2 pivotally mounted thereon at 3 and operated through a power shaft 4 from any suitable source of power, the rotation of this power shaft 4 being transmitted to the sheaf delivery member 2 through a chain and sprocket connection 5 and a resilient pitman connection 6 in such a manner that, as the shaft 4 is rotated, the member 2 is moved alternately back and forth from the full line position shown in Fig. 1 to the dotted line position 80 shown therein, to receive and deliver sheaves to the shocker cradle 7. As in the standard construction, suitable clutch mechanism 8 is provided to control the connection of the shock binding needle 9 to the power shaft 85

4, a cam 10, a member 11, movable with the sheaf delivery member, and means 12 actuated thereby being connected to the clutch and controlling the same in a well-known manner. Further, as in the usual construc-

tion, a clutch 13 is provided to control the connection of the member 2 to the power shaft 4, this clutch, in this instance, being controlled by a resiliently connected, longitudinally disposed, tripping member 14, 95 having a plurality of upstanding arms 15 protruding up into the path of the sheaves delivered from a binder deck 16. As in the usual construction, the binder is equipped with discharge mechanism 17, packer arms 100 18, sheaf ejectors 19 operatively connected to the packer arms, and the other operative and usual parts of the binding mechanism of a binder of standard construction; the sheaf delivery member 2 and trip 14 being 105 positioned on a support 20 projecting out under the binder deck in such a position that when the sheaves are ejected by the dis-

charge arms 17, they will engage the tripping arms 15 at a point above the sheaf delivery member 2.

In my improved construction, instead of delivering one sheaf at a time, two sheaves are delivered, and means are provided for maintaining these sheaves in parallel relation so that they may be delivered to the shocker cradle 7 in parallel relation and in this way build a compact shock, the sheaves being deposited in a predetermined fixed relation in the cradle, being held closely together as they are carried backward by the tines of the sheaf delivery fork and automatically acting, through the resiliency of their butts, upon release from the tines, to spread in the cradle to form a shock having a wide butt. As shown, the fork 2 is of materially greater width than it has heretofore been the practice to make the same, the tines thereof being of such a width that they will pierce two sheaves when the latter are in parallel relation, as shown in Fig. 2. Further, the trip arms 15, instead of performing only one function, as in the previous constructions; namely, that of actuating the clutch mechanism, in this construction are made to perform not only that function, but two added functions; namely, that of supporting the first sheaf as it is ejected by the discharge arms 17 and kicked off the binder deck by the kicker forks 19, and compressing the sheaves together. It is to be noted that each of the supports 15 is made with a substantially L-shaped top and that two of the same are provided on the front end of the trip rod 14, so that a substantial support is provided for the outer sheaf, and one which underlies the sheaf at points on opposite sides of the twine. Attention is further directed to the fact that these members are so disposed with respect to the tines on the fork 2 that there is no conflict between the latter when the fork is raised in the usual operation of the device, the tines on the latter passing freely by the same. As in the usual construction, wherein a sheaf is maintained upon the binder deck after binding and not shoved off the binder deck until the next sheaf is bound, a supplemental deck 21 is also provided, formed of bowed spaced strips fixed at their grainward ends to the binder deck 16, the kicker forks, or sheaf ejectors, moving upward between these strips in a well-known manner. In addition to this supplemental deck 21, however, I provide in this instance a second supplemental deck fixed to the ends of the strips and formed of a plurality of spaced stubblewardly protruding members 22. These members are in the form of metal rods of rounded construction and extending out over a little less than half of the fork, so that there can be no conflict between the same and the tines on the fork 2 as the latter is

raised. Further, in order to avoid this conflict, these rods 22 are made resilient so that they may yield even if by any chance they should be caught by the fork as it passes up and over to sheaf delivering position. Co-operating with the mechanism just described, and operating to hold the first sheaf upon the rods 22 in the position shown in full lines in Fig. 2, is a sheaf holder 23, which is pivoted at 24 to a stationary part 70 of the sheaf discharging mechanism at a point above the deck 22, and extends downward in the form of a hook so that it is in the path of the sheaf as the sheaf moves outward, and when the latter passes beyond 75 the kickers 19, acts to engage the sheaf and hold it securely in position, effectually preventing twisting of the sheaf on the deck or the delivery thereof to the fork in any other than a parallel relation; all troublesome disarrangement of the sheaves in the shock as it is built in the cradle being thus avoided, and the advantageous swinging of the fork tines up to the wood in the sheaves being thus obtained. It is also to be noted 80 that this member 23 is resiliently connected at its inoperative or grainward end by a spring 25 to the stationary part of the discharge mechanism, so that as the sheaf is carried upward by the sheaf delivery arm, 85 it is free to be disengaged therefrom and is automatically swung backward into the path of the next sheaf.

The operation of the construction shown is as follows: As the harvester binding mechanism operates in its usual manner, the packers 18 are actuated, the same moving back and forth through the binder deck 16 and simultaneously operating the kicker arms 19, which likewise move back and forth 100 with an irregular intermittent movement, kicking out the sheaf on the supplemental deck 21 until it occupies the position shown in full lines in Fig. 2, wherein it is positioned upon the rods 22 and above the fork 2 by the resilient member 23. When the next sheaf is bound, it is likewise forced through the same path, the kicker arms 19 forcing the same up against the first sheaf and forcing that sheaf outward to the dotted line position shown in Fig. 2, wherein it is supported on the horizontal portions of the trip arms 15, the second sheaf taking its original place on the rods 22. It is to be noted that in this position: *i. e.*, when the two sheaves are passed together parallel to each other and in the same plane above the fork 2, and substantially parallel to the ground, the trip 14 is pressed back by the stubbleward sheaf, throwing the sheaf delivery member 2 into operative engagement with the power shaft by its actuation of the clutch 13, so that the member 2 is raised through the pitman connection 6, causing its tines to simultaneously pierce both sheaves 110 115 120 125 130 135

and carry the same over in parallel relation to the position shown in Fig. 3, wherein they are deposited on the bottom of the cradle when the fork occupies the position 5 shown in dotted lines in Fig. 1. Obviously, as in the standard shocker construction, the sheaf delivery member 2 will then be returned to its initial full line position shown in Fig. 1, clearing the ends of the rods 22, 10 and the trip arms 15 will have likewise been returned to their initial position so that, as the next sheaves are ejected, the sheaf delivery mechanism is again ready to operate. It is, of course, to be understood that with 15 the mechanism just described any suitable shock binding mechanism may be used; as, for instance, the binding needle 9 thrown into operation automatically when the clutch 8 is actuated by the tripping mechanism 10, 11, 12, the size of the shock thus determining the time of operation of this binding mechanism. Further, the shocker cradle 7 may be operatively connected to the binding mechanism through connections 26 between the latter and the knoter shaft 27, which actuates the binding needle. These, 20 however, specifically form no part of my present invention and, therefore, need not be specifically described.

30 It is to be noted that in this construction the two sheaves are positioned in parallel relation in a plane parallel to the fork and pressed together prior to being pierced by the fork and are so supported that the fork 35 may readily pierce them from below in such a manner as to securely position them thereon. It is further to be noted that while under compression they are delivered to the cradle in parallel relation, to build a shock 40 in tiers of twos; the fork being separated from them just prior to their engagement with the bottom of the cradle, so that their butts are free to spread automatically when they touch the bottom of the cradle in such 45 a manner as to form a shock having a wide butt. Attention is also directed to the fact that by the use of this improved mechanism it is only necessary for the sheaf delivery arm, and therefore all of the sheaf delivery 50 mechanism of the shocker, to operate half as many times during the shocking of a given area, as would a device of the type wherein the fork carries one bundle, the wear and tear upon the parts being thus 55 materially reduced and the life of the machine materially increased. It is also to be noted that, due to the building of the sheaves in parallel relation in such a manner that the butts may be spread subsequently, it is 60 unnecessary to provide any deflecting mechanism for the fork, the cost of manufacture and assembly being thus also materially reduced.

65 While I have in this application described one embodiment which my invention may

assume in practice, it is, of course, to be understood that the form shown herein for purposes of illustration may be modified without departing from the spirit of my invention.

70 What I claim as my invention, and desire to secure by Letters Patent, is:

1. In combination, a harvester, a prostrate shocker cradle operatively connected thereto, and a single means intermediate 75 said harvester and cradle simultaneously positioning side by side and prostrate in said cradle a plurality of sheaves discharged from said harvester.

2. In combination, sheaf discharging 80 mechanism, sheaf delivery mechanism including an oscillating sheaf delivery member, and means for supporting in the path of said member the load therefor discharged by said discharging mechanism.

85 3. In combination, sheaf discharging mechanism, sheaf delivery mechanism including an oscillating sheaf delivery member, and means for supporting in the path of said member a plurality of sheaves discharged by said discharging mechanism.

90 4. In combination, a binder deck, sheaf discharging mechanism adjacent thereto, means for supporting a sheaf discharged by said mechanism adjacent the edge of 95 said deck, and sheaf delivery means including an oscillatory sheaf delivery member movable upward about its pivot into engagement with said sheaf when so supported.

100 5. In combination, a binder deck, sheaf discharging mechanism adjacent the same, means for supporting a sheaf discharged by said mechanism in parallel relation to the edge of said deck, and sheaf delivery means 105 including a swinging sheaf delivery member movable in a fore and aft direction and into engagement with said sheaf when so supported.

110 6. In combination, a binder deck, sheaf discharging mechanism adjacent the same, means for supporting a plurality of sheaves discharged thereby in parallel relation adjacent the edge of said deck, and means including sheaf delivery means movable into 115 engagement with said sheaves when so supported.

120 7. In combination, a binder deck, sheaf discharging mechanism adjacent the same, means for supporting a plurality of sheaves 120 discharged thereby in parallel relation adjacent the edge of said deck and substantially parallel to the ground, and a sheaf delivery member movable upward into engagement with said sheaves when so supported.

125 8. In combination, a harvester, a shocking machine, an upwardly movable sheaf delivery member on said shocking machine disposed in a plane below the deck of said 130

harvester, and means for positioning a plurality of sheaves in the path of said sheaf delivery member.

9. In combination, a harvester, a shock⁵ing machine, a swinging sheaf delivery member on said shocking machine normally disposed in a plane below the deck of said harvester, and means for holding a plurality of sheaves under compression in the path of said sheaf delivery member.

10. In a harvester, a binder deck, sheaf discharging mechanism adjacent the same, means for supporting a plurality of sheaves discharged therefrom in parallel relation adjacent the edge of said deck, a sheaf receptacle, and means engaging said sheaves when so supported, depositing said sheaves in said receptacle in a single operation.

11. In combination, a binder deck, sheaf discharging mechanism thereon, sheaf delivery means including a swinging sheaf delivery member movable upward and rearwardly in a plane beyond the edge of said deck, and means for supporting a sheaf discharged by said discharging mechanism in the path of said member.

12. In combination, a binder deck, sheaf discharging mechanism thereon, sheaf delivery means including a swinging sheaf delivery member movable upward in a plane beyond the edge of said deck, and means coöoperating with said deck and supporting a plurality of sheaves discharged by said discharging mechanism in the path of said member.

13. In combination, a shocker, a binder deck, automatic sheaf discharging mechanism adjacent the same, means for supporting a sheaf discharged therefrom in parallel relation to said binder deck at a point beyond the edge thereof as the next successive sheaf is moved to a position on the edge of said binder deck by said discharging mechanism, and means for delivering the sheaves so positioned to the shocker.

14. In combination, a harvester, a shock⁵⁰ receptacle operatively connected thereto, means for positioning a plurality of sheaves discharged from said harvester in front of said receptacle and in a plane parallel to the ground, and means maintaining the same in the same positions relatively to each other and while so held delivering said sheaves to said shock receptacle.

15. In combination, a harvester, a shocker operatively connected thereto, means compressing in parallel relation a plurality of sheaves delivered from said harvester, and means holding the same under compression and while so held delivering the same to said shocker.

16. In combination, a harvester, a shocker operatively connected thereto, means pressing together and holding a plurality of sheaves discharged from said harvester in

parallel relation and substantially parallel to the ground, and means maintaining the pressure thereon and while so held delivering said sheaves to said shocker and freeing the same as said sheaves are deposited in said shocker.

17. In combination, a harvester, a shocking machine operatively connected thereto, means supporting a plurality of sheaves in parallel relation adjacent the binder deck of said harvester and in a plane substantially parallel to the ground, and means automatically controlled by the sheaves piercing the same when in that relation and delivering the same to the shocker.

18. In combination, a harvester, a shocker cradle operatively connected thereto and trailed at the rear thereof, means positioning a plurality of sheaves beyond the edge of the binder deck of the harvester and substantially parallel to the ground, and means carried by said shocker piercing said sheaves when so positioned and delivering them to said cradle.

19. In combination, a harvester, a shocker cradle operatively connected thereto and trailed at the rear thereof, means positioning a plurality of sheaves beyond the edge of the binder deck of the harvester substantially parallel to the ground, and means carried by said shocker and controlled by said sheaves piercing the same when in that relation and delivering the same to said cradle in the same relation.

20. In combination, a binder deck, means for discharging a sheaf therefrom, sheaf delivering mechanism including a sheaf delivery member normally disposed in a position below said binder deck, and means controlling the operation of said sheaf delivery member supporting a discharged sheaf in the path of said member.

21. In combination, a binder, a shocker operatively connected thereto, an oscillating sheaf delivery member carried on said shocker, and coöperating means carried on said binder and shocker for supporting the load for said member after its discharge by said binder in the path of said member.

22. In combination, a binder, a shocker operatively connected thereto, an oscillating sheaf delivery member carried on said shocker, and means carried on said binder and shocker for supporting a plurality of sheaves discharged from said binder in the path of said sheaf delivery member.

23. In combination, a binder, a shocker operatively connected thereto, a normally prostrate oscillating sheaf delivery fork carried on said shocker and operatively connected thereto, and means positioning a plurality of sheaves discharged from said binder in compressed relation above said fork when the latter is in prostrate position.

24. In combination, a binder, a shocker

5 operatively connected thereto, an oscillating sheaf delivering fork carried on said shocker, and means for simultaneously compressing and positioning a plurality of sheaves discharged from said binder in parallel relation in the path of the tines on said fork and for automatically actuating the latter when the sheaves are in said position.

25. In combination, a binder, a shocker 10 operatively connected thereto, and means for positioning a plurality of sheaves discharged from said binder in a predetermined relation with respect to said shocker and said binder and intermediate the same, and separate means delivering said sheaves in the same relation to said shocker.

26. In combination, a binder, a shocker coöperating therewith, a sheaf delivery member on said shocker, a sheaf receiving member thereon, and means successively positioning a plurality of sheaves discharged from said binder in parallel relation to the sheaf delivery member of said shocker and automatically actuating said delivery member to 25 deliver said sheaves simultaneously to the sheaf receiving member thereof.

27. In combination, a harvester, a binder deck thereon, a shocking machine trailing at the rear thereof, a swinging sheaf delivery 30 member carried on said shocker and normally disposed in a plane below the binder deck of said harvester, and means carried by said harvester and said shocker supporting a plurality of sheaves in parallel relation in the path of said sheaf delivery member.

28. In combination, a harvester, a binder deck thereon comprising a plurality of spaced resilient rods, a shocker operatively 40 connected to said harvester, a swinging sheaf delivering fork on said shocker normally disposed in a plane below said deck, and means carried on said shocker and controlling the operation of said fork supporting a 45 sheaf above said fork.

29. In combination, a harvester, a binder deck thereon, a shocker attached to said harvester, a sheaf delivery member on said shocker normally disposed in a plane below said binder deck, clutch mechanism controlling the connection of said sheaf delivery member, and a clutch tripping member carried on said shocker and having upstanding arms provided with horizontal portions 55 adjacent the edge of said deck.

30. In a harvesting machine, a binder deck; sheaf discharging mechanism carried

thereon, a supplemental deck forming an extension of said binder deck, and supplemental means carried on said binder deck automatically engaging a sheaf deposited on said supplemental deck by said discharging mechanism and retaining the same thereon automatically releasable upon the next actuation of said discharging mechanism.

31. In a harvester, a binder deck, a supplemental deck forming an extension thereof, sheaf discharging mechanism carried adjacent said binder deck delivering a sheaf therefrom upon said supplemental deck, and a sheaf engaging hook pivoted to said discharging mechanism and controlled thereby having one end projecting over said supplemental deck and its opposite end resiliently connected to a stationary part of said discharging mechanism.

32. In a shocking machine, a binder deck, sheaf discharging mechanism, a sheaf delivery member disposed beneath said deck, laterally extending fingers carried on said 80 deck and disposed part way over said member, and means for moving said member into engagement with a sheaf resting on said fingers.

33. In a shocking machine, a binder deck, 85 sheaf discharging mechanism, a sheaf delivery member disposed beneath said deck, laterally extending spaced resilient fingers carried on said deck and disposed part way over said member, and means for moving 90 said member into engagement with a sheaf resting on said fingers.

34. In combination, a harvester having a binder deck, a shocker operatively connected to said harvester, a sheaf delivery fork 95 having its tined end normally supported in a plane below and at the delivery side of said binder deck, extensions on said binder deck protruding transversely of said sheaf delivery member, clutch mechanism carried 100 on said shocker controlling the operation of said sheaf delivery fork, and means carried on said shocker supporting a sheaf ejected from said binder deck and actuated by the same to set said sheaf delivery fork in operation to pierce the sheaves supported 105 thereon and in parallel relation thereto on the extensions on said binder deck.

In testimony whereof I affix my signature, in the presence of two witnesses.
